(57) **CLAIM**

The ornamental design for a drone battery arrangement as shown and described.

DESCRIPTION

FIG. 1 is a top, rear, left side perspective view of a drone battery arrangement showing my new design;

FIG. 2 is a top, front, right side perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof;

FIG. 8 is a top, front perspective view thereof; and

FIG. 9 is a top, rear perspective view thereof.

FIG. 10 is a detailed top, front, left side perspective view of the front battery in the design shown in FIG. 1 in a closed position;

FIG. 11 is a detailed top, front, left side perspective view of the front battery in the design shown in FIG. 1 in an open position;

FIG. 12 is a detailed top, front, left side perspective view of the rear battery in the design shown in FIG. 1 in a closed position; and,

FIG. 13 is a detailed top, front, left side perspective view of the rear battery in the design shown in FIG. 1 in an open position.

The dark shaded body of a drone shown in FIGS. 1-9 is for the purpose of illustrating environmental structure and forms no part of the claimed design.

The dark shading shown in FIGS. 10-13 is for the purpose of illustrating portions of the drone battery arrangement that form no part of the claimed design.

1 Claim, 11 Drawing Sheets
